UNITED STATES PATENT OFFICE

CHARLES GILBERT HAWLEY, OF CHICAGO, ILLINOIS, ASSIGNOR TO CENTRIFIX CORPORATION, OF CLEVELAND, OHIO, A CORPORATION OF OHIO

LOCOMOTIVE-BOILER-OUTPUT CONTROL

Application filed March 5, 1926. Serial No. 92,478.

My invention relates to a method of and means for controlling the steam output of boilers to the end that the steam shall leave the same in a dry and clean state or reversely 5 to the end that the boiler water shall be retained in the boiler and prevented from escaping at the steam outlet along with the steam.

In the operation of steam boilers generally, 10 and particularly, in the case of steam locomotives and marine boilers serious difficulties are experienced because of the surging of the boiler water. Added to by the violent and unequal liberation of steam at different points 15 in the boiler, the surging so disrupts the steam disengagement surface as to throw masses or slugs of water into the steam space, with the result that much of it is carried away through the outlet or nozzle by the escaping steam. 20 Thus, the steam leaving the boiler becomes a vehicle for moisture and solids and in many instances large quantities thereof pass into the engines, turbines, and other steam units, which should receive only dry clean steam 25 from the boiler. Any steam superheater that may be interposed is likewise fouled and rendered inefficient.

The objects of my invention are to overcome these difficulties and to avoid the maintenance and equipment costs involved thereby.

As will become apparent, my invention in several of its embodiments, is of general applicability and will be found to be of advantage in all steam boilers and evaporators, 35 whether working under pressure or vacuum. But in the drawings that form part of this specification, the invention is illustrated in that form which seems best adapted to locomotive boilers, where the difficulties to be surmounted are the greatest.

In the drawings, Fig. 1 is a transverse vertical section of a typical steam locomotive boiler equipped with the structures that embody the present invention.

Fig. 2 is a horizontal section on the line $x-x$ of Fig. 1.

Fig. 3 is a vertical longitudinal section of the same boiler and structures except that the 50 throttle valve is replaced by an open stand-

pipe and the pool structure is also somewhat modified.

Fig. 4 is a horizontal section on the line $y-y$ of Fig. 3.

It will be seen that only the upper middle 55 portion of the locomotive boiler is shown in the drawings. The wrapper sheet is marked 2. The upper forward corner of the fire box is marked 3, and the flues 4. The shell or barrel of the boiler is marked 5, and the dome, 6, 60 and the dome cap, 6'. The steam outlet or so-called drypipe is marked 7, and, as usual, leads to the front end of the boiler. At the rear end of drypipe is a standpipe 8, which extends into the top of the dome. As shown 65 in Fig. 1, the standpipe may be equipped with a throttle valve 9, or it may have a simple open upper end, as shown at 10 in Fig. 3, the latter being characteristic of a construction in which the throttle valve is arranged at the 70 forward end of the drypipe, usually in the smoke box.

The part of the shell or barrel which is covered by the dome 6, contains a large opening 11, through which the standpipe 8 rises; and 75 through which access may be had to the interior of the boiler when the dome cap 6' is removed.

The normal water level is indicated by the line WL. The surface thus indicated will 80 also be referred to as the steam disengagement surface. In modern locomotives, the boilers are of such great size as to leave little clearance space at the top and the steam domes are very low. Perforce, the said disengagement 85 surface dangerously approaches the level at which the steam escapes into the top of the standpipe or outlet. Unless preventive means be used it is inevitable that water shall be elevated from the disengagement surface and 90 discharged through the outlet with the steam. As steam outlet velocities ranging from 6,000 to 12,000 feet per minute are common, it should be apparent that although moderately dry steam is secured from high domed, small 95 locomotive boilers, in the case of the larger locomotives the supply of dry steam is defeated, for, in fact, every tendency seems to be directed toward emptying the boiler of water, as well as of steam. These tendencies 100

are aggravated whenever the disengagement surface is fouled with impurities and worse when actual foaming conditions are encountered. They are augmented when the boiler is fired at high ratings, at which times the disengagement surface is violently agitated by the numberless ascending steam bubbles from the evaporating surfaces of the boiler. And, further, the forces tending to elevate the water and discharge it at the steam outlet are made more certain of action by the surging and splashing of the boiler water as the locomotive lurches and rolls upon the rails and at times when the brakes are applied and with every sudden curve and change of grade. Such motions of the boiler throw quantities of water into the steam space and result in "slugging" the dry-pipe, the superheater, the valves and the engines, and even the auxiliary steam users such as the air compressor and the head light turbine are affected.

The major difficulties encountered have been described at greater length than usual in order that the simple constructions involved in this invention may be better appreciated and more clearly understood.

The primary element of the present invention is the part or structure to which I have given the name "pool". It is in fact a relatively quiet pool of boiler water, set aside or separated from the major disengagement surface. This pool is defined by a substantially imperforate encompassing wall that rises from a point below the safe low water level in the boiler and extends nearly to the top of the boiler shell. This pool is located around and beneath the steam outlet; in this case directly beneath the steam dome. As will become clear, the dip of the wall into the boiler seals off the lower end of the pool as a steam entrance, except for such steam as may be disengaged from the surface of the water lying within the pool itself. Thus the steam must find another path over which to reach the steam dome and outlet. To reach the latter, the steam from the major disengagement surface must pass over or through the top of the pool defining wall. As will be explained in detail, any particles and masses of water that may be carried by the steam are there caused to strike surfaces by which they are thrown down into the pool of water within the confines of the encompassing wall. The steam having been freed of its burden of moisture rises freely above the pool and passes into the dome, thence to enter the steam outlet or drypipe. The main volume of steam enters in this manner. A minor volume of steam, important in its effects, rises directly within the pool being disengaged from the surface thereof.

From the foregoing it should be evident that while my invention perhaps meets the greatest need in the case of locomotive boilers, it is also generally applicable to all boil-

ers and evaporating vessels, being well adapted for use wherever vapor is released from a disengagement surface of sufficient extent to admit of this described subdivision and is so close to or in such restricted communication with the steam outlet as to require definite measures to prevent the carrying over of entrained moisture. 70

In the drawings, the above described steam pool is marked P and will be seen to be defined by the encompassing wall W. This wall is preferably cylindrical, as well shown in Figs. 2 and 4. As there shown it is composed of vertically separated curved sections; two of these 12—12 meet above and below the dry-pipe 7. The pair of sections 13—13 are at the sides and the section 14 is at the rear side or end, opposite the standpipe 8. The edges of the sections are joined by the hereinafter described hangers 21 and a plurality of easily removable bolts 22. As access to the boiler here shown is gained through the dome, all of the fastenings 21—22 are placed upon the inner side of the part or wall W; and it will be understood that the part W is of such generous size as to easily accommodate a man. 85

The open lower end 17 of the wall W (and pool P) is somewhat above the flues 4, to avoid wear on the latter. The upper end of the wall W closely approaches the under side of the boiler shell and is there equipped with a circular series of tangential tuyères which latter constitute the main steam entrance; and will be described in detail. A sectional splash flange 19 is preferably used upon the exterior 90 of the wall W just below the said tuyères.

The depending collar or sleeve 20 has two important functions. It is spaced inwardly from the wall W and forms a baffle which prevents the direct passage of the steam from the tuyère level into the dome. Second, the sleeve or collar 20 serves as a support from which the wall, W, hangs, as through medium of aforesaid hanger bars 21. Except for the reasons cited below, the upper ends of the hangers, 21, may be riveted or otherwise permanently fastened to the depending collar. Their lower ends are attached to the wall sections by aforesaid keys or bolts 22. As a rule only the wall section 14 need be removed to permit entrance to the interior of the boiler but at times all of the sections should be taken up. Hence, the employment of the detachable hanger fastenings 22. Obviously, the upper end of the collar 20 is conveniently fastened to the walls of the dome opening 11. Where this is not feasible the collar should be hung close against the under side 5' of the boiler shell; for in every case the collar is desirable as a means to fill the opening 11 and prevent the direct passage of steam from the body of the boiler into the dome. 115

The two tuyère arrangements are shown, one in Figs. 1 and 2, and the other in Figs. 3 and 4. 120

5 The tangential, or whirl promoting tuyères 15 of Fig. 1 are disposed preferably in a horizontal plane between the upper edge of the pool wall W, and the lower edge of the supporting or baffle collar 20. As shown, they open downward and are formed by blades 16 that lap one under the other in series. Together they provide a steam entrance passage 10 of an area that is preferably considerably larger than that of the steam outlet in the upper end of the drypipe 7. The generous tuyère openings give the needed moisture precipitating effect without organizing so forcible a downward movement of steam and water as to materially agitate the surface of the pool. As before intimated, the moisture thus separated from the steam is retained in the pool while the freed steam moving toward the axis of the pool ascends quietly to the outlet.

20 The whirl promoting structure of Figs. 3 and 4 is of the same effect as above described. But it comprises a circular series of longitudinal tuyère blades 17, which form or define the many tangential tuyères 18, all of which lead inward. In this form the tuyères possess the capacity of promoting the described whirling action of the steam and the throwing down of the entrained moisture with less disturbance of the surface of the pool.

25 Special attention is called to the fact that the steam pool occupies only a very minor part of the disengagement surface. Further, the pool defining wall or structure is of such moderate width that it occupies only a minor part of the transverse section of the boiler. Thus, the spaces S', S' on opposite sides of the pool are left amply large to permit an inspector or workman to move along the tops of the flues from end to end of the boiler.

40 Generally, the surface WL is in a very disturbed state, due to the ebullition of the water. And the water splashes heavily from side to side and end to end when the locomotive is in motion. In consequence, the steam space S is filled with steam that usually is heavily overburdened with particles and masses of water. The burdened steam enters the many tangential tuyères at the top of the 45 pool and by virtue thereof is caused to swirl downward against the inner surface of the cylindrical pool wall. Thus the heavier water is caused to plunge into the relatively quiet water of the pool, leaving the steam free to rise into the dome with little if any burden of moisture.

Attention is called to the fact that the steam entrance tuyère openings at the top of the steam pool may be so restricted as even to 50 wire-draw the steam. It is a question whether the downwardly deflecting action is or is not improved by restricting the capacity of the tuyère opening. The aggregate opening may be so restricted as to make its area little greater than the area of the throttle valve and dry-

50 pipe. This notwithstanding the fact that an apparent drop of pressure within the pool would cause the elevation of the surface of the water therein. Such elevation will not take place. Indeed, it is a feature of my invention to prevent a drop of pressure within the pool. This prevention is accomplished very simply, to wit: By the accelerated evaporation of steam from the surface of the pool;—a natural and inevitable result of any 55 tendency toward a lower pressure within the pool. To the end that this feature of my invention shall be clearly understood, attention is again directed to the fact that the boiler is assumed to be in operation under steam 60 and that the surface of the pool is no more than a part of the whole disengagement surface WL.

Various modifications and adaptations of my invention will readily suggest themselves 65 to those who are skilled in the art of separating entrained moisture from vapors and I desire that it be definitely understood that my invention is not limited to the precise structures herein shown and described.

Having thus described my invention, I 70 claim as new and desire to secure by Letters Patent:

1. A boiler having a dome which contains the vapor outlet, in combination with a separable sectional whirl promoting pool structure hanging within the boiler, below said dome and accessible through the latter, said structure extending from the top of the boiler to a point below the liquid level in the boiler.

2. A boiler having a dome, in combination with a standpipe positioned in said dome and containing the vapor outlet, a whirl promoting pool structure surrounding said standpipe below said dome, the bottom of said 90 pool structure opening into the boiler at a point below the liquid level therein and detachable means for supporting said structure from the base of the dome and accessible from the interior thereof.

3. A boiler having a dome, in combination with a vapor outlet leading from said dome, a pool structure positioned beneath said dome, extending below the water level and enclosing a large portion of the steam disengagement surface in the boiler and centrifugal steam wringing means positioned at and forming the top of said pool structure.

4. A locomotive boiler having an opening in its top, a dome positioned above said opening, a dry pipe leading from the dome and downward through said opening, an annular wall structure of larger diameter than said opening and suspended from the top of the 125 boiler co-axially with said opening, said structure extending downward to a point below the low water level in the boiler, and whirl promoting tuyères disposed at the top of said structure, and said tuyères, the space within 130

said wall structure, said opening and said dome constituting the avenue through which steam within the boiler surrounding said wall structure is conducted to said dry pipe.

⁵ In testimony whereof I have hereunto set my hand this 3rd day of March, A. D. 1926.

CHARLES GILBERT HAWLEY.
